UNITED STATES PATENT OFFICE.

HENRY H. C. EICHELBERGER AND HILARY W. BRUNER, OF CROCKETT, TEX.

SPRING BED-BOTTOM.

SPECIFICATION forming part of Letters Patent No. 248,415, dated October 18, 1881.

Application filed June 11, 1881. (No model.)

To all whom it may concern:

Be it known that we, H. H. C. EICHELBERGER and H. W. BRUNER, of Crockett, in the county of Houston and State of Texas, have 5 invented certain new and useful Improvements in Spring Bed-Bottoms; and we do hereby declare that the following is a full, clear, and exact description of the invention, which will enable others skilled in the art to which it applies to make and use the same, reference being had to the accompanying drawings, which form a part of this specification.

In the drawings, Figure 1 is a plan view, and Fig. 2 a side elevation.

15 Corresponding parts in both figures are denoted by the same letters of reference.

This invention relates to springs to form bed-bottoms, and has for its object to construct a series of spring-coils of one piece of wire, which 20 is accomplished by certain improvements in the construction and arrangement of the springs, substantially as will be hereinafter described, and particularly pointed out in the claim.

25 Referring by letters to the drawings, A designates a pair of twin springs, connected by a horizontal connecting-coil, B, and having the wire of one of the coils or springs continued diagonally under the bed-slat, as at C, and from thence upward to form the first spiral coil of the next set, A', and extending to form the connecting-coil B' and next spiral, from which the wire passes again diagonally under the bed-slat, as at C', and so on until any desired number of 30 coils or spirals are constructed. When the end of the slat is reached the wire may be continued

across to the adjoining slat and the same formation of coils followed; and in this manner, as will be obvious, an entire bed-bottom may be made of a single piece of wire, and thus save 40 the expense and inconvenience of coils becoming detached or lost.

We are aware that a double coil of springs has been formed before and connected at their tops by a diagonal piece extending from slat to slat, 45 the connecting-piece being integral with the coil; but such we do not claim as of our invention.

From the foregoing description the operation and advantage of our invention will be readily 50 understood. It is simple in construction, inexpensive, and far more comfortable than single or separate springs of a similar construction.

We claim—

The herein-described method of forming 55 spring bed-bottoms of one piece of wire, which consists in continuing the wire of one coil or spiral diagonally under the bed-slat, and from thence upward to form a second coil or spiral, and thence horizontally across to form a third 60 coil, and so on in like manner until the desired number of coils have been formed and attached to the slats, as and for the purpose set forth.

In testimony that we claim the foregoing as 65 our own we have hereto affixed our signatures in presence of two witnesses.

HENRY H. C. EICHELBERGER.
HILARY WENTZ BRUNER.
